(57) CLAIM

I claim the ornamental design for a candle holder, as shown and described.

DESCRIPTION

FIG. 1 is a front perspective view of a candle holder;

FIG. 2 is an alternative front perspective view thereof;

FIG. 3 is an alternative front perspective view thereof;

FIG. 4 is a rear perspective view thereof;

FIG. 5 is a front view thereof;

FIG. 6 is a side view thereof;

FIG. 7 is a rear view thereof;

FIG. 8 is a top view thereof; and,

FIG. 9 is a bottom view thereof.

The broken lines form no part of the claimed design.
